UNITED STATES PATENT OFFICE

165,924

FOOD MIXER POWER UNIT

Donald L. McFarland, Stratford, and Bradford R. Voight, Milford, Conn., assignors to General Electric Company, a corporation of New York

Application April 11, 1951, Serial No. 14,794

Term of patent 14 years

(Cl. D44—1)

To all whom it may concern:

Be it known that we, Donald L. McFarland and Bradford R. Voight, citizens of the United States, and residing, respectively, at Stratford, in the county of Fairfield, State of Connecticut, and at Milford, in the county of New Haven, State of Connecticut, have invented a new, original, and ornamental Design for a Food Mixer Power Unit, of which the following is a specification, reference being had to the accompanying drawing, forming a part hereof.

Figure 1 is a perspective view from the front and one side of the food mixer power unit, showing our new design; Figure 2 is a side elevation of the opposite side of the food mixer power unit; and Figure 3 is a rear elevation thereof.

We claim:

The ornamental design for a food mixer power unit, as shown.

DONALD L. MCFARLAND.
BRADFORD R. VOIGHT.
